CLAIM

The ornamental design for a baby crib, as shown and described.

DESCRIPTION

FIG. 1 is a first perspective view of a baby crib showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the selected portion 9 in FIG. 2.

The broken lines shown in the drawings depict portions of the baby crib that form no part of the claimed design. The claim is directed to the collective appearance of the baby crib shown in the figures. The relative positioning of the parts forms part of the claimed design.
